(57) **CLAIM**

The ornamental design for a electric mixer, as shown and described.

DESCRIPTION

FIG. 1 is a perspective view of a electric mixer showing my new design;

FIG. 2 is a right side elevation view thereof;

FIG. 3 is a left side elevation view thereof;

FIG. 4 is a front elevation view thereof;

FIG. 5 is a rear side elevation view thereof;

FIG. 6 is a top view thereof;

FIG. 7 is a bottom view thereof.

FIG. 8 is a close configuration view thereof; and,

FIG. 9 is an open configuration view thereof.

The broken lines depict environmental subject matter only and form no part of the claimed design.
